UNITED STATES PATENT OFFICE.

WALTER S. GEMMER AND EMIL J. SCHLEICHER, OF ST. LOUIS, MISSOURI, ASSIGNORS OF ONE-THIRD TO BRODERICK & BASCOM ROPE COMPANY, OF ST. LOUIS, MISSOURI, A CORPORATION OF MISSOURI.

AERIAL TRAMWAY.

No. 867,497.

Specification of Letters Patent.

Patented Oct. 1, 1907.

Application filed February 20, 1907. Serial No. 358,373.

To all whom it may concern:

Be it known that we, WALTER S. GEMMER and EMIL J. SCHLEICHER, citizens of the United States, residing at the city of St. Louis and State of Missouri, have invented certain new and useful Improvements in Aerial Tramways, of which the following is a specification, reference being had therein to the accompanying drawings.

This invention relates to aerial tramway systems, and 10 has for its primary object to provide means for automatically loading a traveling bucket at a station at any desired point in a tramway-line.

Subordinate objects are to provide a movable loading 15 means which is coupled to and carried forward by the traveling bucket for a predetermined distance, the contents of said loader being discharged into the bucket during the period of such travel; to provide means which will automatically uncouple said loader, when unloaded, from the bucket and return same to starting 20 position; to provide means for automatically unloading the loaded bucket whenever desired; to provide a suitable station at which the bucket-loading is accomplished; and to provide improved constructions of various appliances for use in an aerial tramway system.

25 In the drawings forming part of this specification, in which like numbers of reference denote like parts wherever they occur, Figure 1 is a view of a loading station; partly in section and partly in front elevation; Fig. 2 is a sectional view on the line 2—2, Fig. 1, looking toward the right, the framework being in section and the other parts in side elevation, and the movable parts being shown in full lines in starting position and in dotted lines after they have traveled a predetermined distance; Fig. 3 is a top plan view of the loader; 30 Fig. 4 is a top plan view and side elevation of one of the bulkheads which serve to close the openings in the traveling hoppers when same are in starting position; Fig. 5 is a perspective view of one of the traveling hoppers; Fig. 6 shows a guide plate in end and side elevation; Fig. 7 shows one of the actuating levers in side elevation; Fig. 8 shows the connection between the actuating levers and one of the traveling hoppers; Fig. 9 is a detail of the trolley beam and traction-cable clip, in end elevation; Fig. 10 is an end elevation of the 35 bucket-locking devices; and Fig. 11 is a side elevation of the same parts shown in Fig. 9.

The bucket 1, the construction and operation of which are more particularly described in our application for Patent Serial No. 288,130, filed November 20, 50 1905, copending herewith, is supported from the trolley beam 2 by pendant 3, and is pivoted in such position that it will dump its contents automatically when latch 4 is released, from engagement with bracket 5, and, thereafter, will automatically return to upright or load-

ing position. The sheaves 6 are journaled in the trolley beam 2, and travel on the track cable 7 which, at loading stations, preferably terminates in a fixed track 8. Projecting on each side of the trolley beam 2 is a stout pintle 9 which is provided both to support the pendant 3 and to actuate the loading hoppers 10 as the 60 traveling bucket 1, drawn by the traction cable 11, enters a loading station, thus to cause said hoppers to travel synchronously with said bucket until released as hereinafter described. A clip 12 is secured to the trolley beam 2, said clip being tightened so as constantly 65 to engage the traction cable 11, which cable is located above the track cable 7 and track 8.

At each loading station is an ore bin 13 placed above the tramway system, so that its contents will feed downward by gravity, and this bin terminates in chutes 14, 70 one chute being provided on each side of the tramway system. Automatically-operated gates 15 close said chutes when the feed of ore is to be stopped, and, in addition, said gates may be adjusted to regulate the amount of ore which can pass through chutes 14 in any 75 given period of time. Chutes 14 discharge the ore into the traveling hoppers 10 while said hoppers are at rest, and these hoppers, in turn, while moving, empty their contents into bucket 1.

The traveling loader comprises a pair of hoppers 10, 80 which are respectively located on opposite sides of the track cable 7 or track 8 and which are, furthermore, suitably united together to form a unitary structure. Because of this provision and arrangement of a plurality of hoppers, on opposite sides of the path of the bucket 85 1, ore can be discharged into bucket 1 from both sides, instead of from only one, as has heretofore been the practice. Many important advantages have been found to arise from this improved construction, among which may be mentioned the fact that the traveling bucket 90 can be loaded in half the time otherwise required; and the distance which the traveling loader must cover thereby cut in half, so that the cost of constructing the loading stations is materially reduced; the fact that the load of ore is more evenly distributed and more loosely 95 packed in the traveling bucket; so that it will empty more readily and will travel with less tendency to cause the trolley sheaves 6 to bind on the track cable 7, which binding necessarily occurs where the center of gravity of the loaded bucket is very much to one side, as is the 100 case where the ore is unevenly distributed or dumped in a single heap in the bucket; the fact that even distribution tends to reduce many strains on the entire system which would otherwise be present, thereby helping to prolong the life of all parts; the fact that the 105 weight borne by the traveling loader is evenly distributed on each side thereof; and the fact that said loader can be actuated at or near its center of gravity,

at a point midway between the two hoppers, instead of being drawn from one corner or one side as customary in present practice, where the traveling bucket actuates a single hopper, thus allowing the hopper-carriage 5 to move easily and with little, if any, tendency for the sheaves supporting same to bind on or ride off the track on which they travel.

The traveling loader comprises a framework of horizontal I-beams or channel irons 16 and longitudinal I-beams 17, from which beams the hoppers 10 are supported, and by which they are connected. Sheaves 18 are journaled upon suitable axles which are secured either to cross-beams 16, as in Fig. 3, or to longitudinal beams 17, as in Fig. 2, said sheaves traveling upon tracks 15 19, so that the loader can move back and forth on said tracks, carrying hoppers 10 therewith, said hoppers discharging their contents into the bucket 1 while the parts are in motion.

In order to insure the travel of the loader at the same time bucket 1 is passing through the loading station, 20 means are provided for locking said loader to said bucket, or the trolley beam supporting same, and for releasing said members from such engagement at a predetermined point. To this end, pintle 9 projects 25 outwardly from trolley beam 2, as hereinabove set forth, and, as the bucket 1 passes through the loading station, said pintle locks with the pivoted and spring-pressed actuating levers 20, which levers are adapted to cause the loader to start forward slowly but gradually to increase 30 in speed until it travels at the same rate as bucket 1. Said levers, also, serve as a buffer to obviate the shock and jar that would ensue if the rapidly-moving bucket should directly strike the heavily-loaded hoppers 10 or the carriage supporting same while those parts 35 are at rest.

Secured to the outer wall of or countersunk in, each of the hoppers 10, and extending across the space between the same is a shaft 21, upon which shaft are fulcrumed the actuating levers 20. Said shaft may be 40 otherwise mounted, however, as by brackets secured to the framework of the loader. Said levers are disposed in the path of travel of the pintle 9, and are engaged by said pintle as the bucket 1 passes through the loading station. Said actuating levers occupy, when the loader 45 is at rest, the approximately vertical position depicted in full lines in the left-hand end of Fig. 2, and the helical springs 22, one end of each of said springs being secured to one of said levers 20 and the opposite end to shaft 21, tend to keep said levers normally in such vertical position, to resist any forces which operate to pull the levers out of such vertical position, and to return the levers to the position depicted in the left hand end, Fig. 2, when they are so moved by the action of the pintle 9, as presently described.

55 When the pintle 9 strikes levers 20, said levers yield slightly against the resistance of springs 22, but, at the same time, as the pintle presses the levers forward in the same direction as the pintle itself moves, the levers, in turn, cause the loader to move forward as well. As 60 the bucket 1 continues to move and pintle 9 to bear on the inwardly-curved edges 23 of levers 20, the levers are gradually swung upward as the springs 22 yield, the levers, of course, moving forward and causing the loader to travel at a gradually increasing speed, until, finally, 65 the pintle 9 seats in the crotch of the hook-like ends 24,

after which the traction cable 11, being then connected to the loader, will draw the loader along at the same rate of speed as the bucket itself is moved. During the time that the pintle 9 is bearing on edges 23, the loader bearing the hoppers 10 is caused to move forward at a gradually increasing rate of speed as the springs 22 are tightened by the rotation of levers 20 around shaft 21, said loader reaching the maximum velocity when the pintle 9 catches in the hooks 24.

Inasmuch as it is desired to have the loader thus travel for only a predetermined distance and during such length of time as will enable the contents of the hoppers 10 to be discharged into the bucket 1, if it is necessary to release the levers 20 from engagement with pintle 9 at a predetermined point. A shaft 26 75 cross-connects the ends of levers 20 opposite the hook-like ends 24, so that these levers move in unison, and upon said shaft rollers 25 are journaled. In the path of travel of these rollers a releasing-trip 27 is interposed, which trip is adapted to depress the upper ends 80 of levers 20, thereby to elevate the hook-like ends 24 and disconnect the same from the pintle 9. Trip 27 is suspended from the framework of the loading-station and comprises an inclined surface 28 and a horizontal surface 29, rollers 25 riding first upon the incline 28 so that the lever is rocked about shaft 21 as a fulcrum until it reaches the position depicted in dotted lines in the right hand end of Fig. 2, when, obviously, hook 24 will be freed from-pintle 9. Bucket 1 then continues on its way, but the loader is no longer pulled forward, and will come to a stop. It is best, however, to provide a buffer of some kind to prevent the loader from traveling too far, and this buffer may be of any desired form and can be placed wherever convenient.

As one illustration, the drawings show the ends of the 100 rails 19 bent upward at 19° so that sheaves 18 may strike thereagainst, thus positively limiting the forward movement of the loader, as well as imparting a slight return impulse thereto. The rails 19 are set at an incline, so that as the loader moves forward as above 105 described it travels on an up grade. When, however, the levers 20 are released from the pintle 9, the loader is no longer drawn forward, but is free to return to the starting position depicted at the left hand end of Fig.

2. To secure such return and make it automatic, a 110 counterweight 34 may be provided, said counterweight being suspended at one end of a rope 35, which rope passes over a pulley 36 and has its opposite end secured to any convenient part of the loader, as, for example, the beam 16. It is not necessary in all cases 115 to provide this counterweight, and generally it will be found sufficient to set the rails 19 at an incline, so that the carriage can return by rolling down grade. As the loader thus returns, springs 22 cause the levers 20 to resume the vertical position, and, when the loader has 120 returned to the left hand end of Fig. 2, the levers 20 will be in place so that the loader is ready for another trip as soon as the hoppers 10 have been refilled.

When the ore is discharged from chute 14 into hoppers 10 it would fall to the ground were not some means 125 provided for closing the mouth 30 through which the ore passes from the hoppers into the bucket. Accordingly, a bulkhead 31 is secured to the framework of the loading station, said bulkhead being properly braced, as at 32, and so placed that when the hopper 130

10 is in starting position it will bear thereagainst with mouth 30 immediately behind said bulkhead and closed thereby. As hopper 10 is drawn forward (toward the right, Fig. 2) in the manner hereinabove described, mouth 30 gradually rides beyond the end of bulkhead 31, and the ore drops through said mouth (now unobstructed) into the bucket 1 beneath. The edge of the bulkhead flares as at 33 toward the side opposite that against which the hopper rests, so that 10 the loader will slide into position, on its return movement, without having the hoppers 10 strike against the outer edge of said bulkheads.

When the pintle 9 strikes the levers 20, there is a 15 tendency for the reaction to cause the bucket to rise up, and thus derail the trolley sheaves 6 from the track 8. To obviate this, a guide 37 is provided, said guide being bolted or otherwise secured to the loader at 38. The apex of the trolley beam 2, is curved as at 20 39 and, as the pintle 9 strikes levers 20, the curved apex 39 rides underneath guide 37 and bears thereupon, said guide thus holding the trolley beam 2 from rising, so that sheaves 6 can not leave track 8. A spring 40 is, likewise, fastened to the loader and placed in such a position that the curved apex 39 strikes thereagainst 25 before coming into contact with the guide 37, the spring thereby serving partly to absorb the shock which occurs when the traveling bucket picks up the loader to carry same forward. In lieu of having the apex 39 curved, a roller may be journaled in the trolley beam 30 or on pintle 9, said roller, instead of the curved top 39, striking against guide 37, this construction being, in many cases, the preferred form.

To each of the arms 41 of pendant 3 plates 42 are secured, and in these plates latches 4 are pivoted, there 35 being one such latch at each side of bucket 1, said latches being adapted to hook over the projecting ends of brackets 5, and thereby keep the bucket 1 locked in upright position. A shaft 43 is journaled in blocks 44 which are fixed to the pendent arms 41. Links 45, eccentrically pivoted to the ends of shaft 43 or to crank-arms 46 which are fixed upon said shaft, connect the shaft to latches 4, so that rotation of the shaft causes links 45 to raise the latches 4 and thereby allow the bucket 1 to be released so as automatically to dump its 40 contents. A handle 47 is secured to shaft 43, and a trip 48, similar in construction and arrangement to trip 27, can be placed at any desired point in the system, said trip serving to depress the handle 47, and, thereby, to release the bucket so that it will discharge its contents 45 automatically.

The trolley beam 2 is preferably triangular in shape, the sheaves 6 being journaled adjacent the two lower angles while the pintle 9 passes through the beam near the apex thereof. Pintle 9, in addition to serving as a 50 convenient means for actuating the loader, is the axis for roller 39, and, further, supports the bucket 1 from the beam, pendant 3, in which the bucket is held, looping over said pintle. Projecting outwardly from trolley beam 2 at a point below pintle 9 is an extension 49 upon 55 which clip 12 is mounted, said clip being provided to engage the traction cable 11 by which the various moving parts are drawn forward.

To each ore gate 15 one arm of a bell-crank lever 50 is secured; said lever, on being rocked, serving to open 60 the gate. An operating lever 51, fixed to a rock-shaft

52, rocks said shaft, and swings the crank arm 53 which is fixed upon said shaft. As said arm 53 is swung, link 54 is pulled, thus rocking the bell-crank 50 and thereby opening the gate 15. It should be understood that the levers 51 are moved automatically so that the gates 15 70 are opened at the proper time to fill the hoppers 10, and are closed as soon as a sufficient quantity of ore has passed down the chutes 14. Said automatic mechanism, however, forms no part of the present invention, and is not herein described or shown in detail, the levers 51 being represented conventionally and as capable of manual operation only.

The operation of the system is as follows: The clip 12 having been tightened upon the traction cable 11, said cable draws the bucket 1 forward (toward the right, Fig. 80 2), said bucket being supported from the trolley beam 2 which travels on track 8 or cable 7. As bucket 1 enters the loading station, pintle 9 engages the levers 20, and, as the trolley beam 2, which carries the pintle, continues to move forward, levers 20 are simultaneously 85 pressed forward and upward, thus actuating the loader and causing same to travel at a gradually increasing rate of speed until, at length, pintle 9 engages the hook-like ends 24 of levers 20, after which the loader and the bucket 1 will travel in unison for a predetermined time. 90 When the upper ends of levers 20 strike the trip 27 and are depressed thereby, the hook-like ends are elevated and thus forced out of engagement with the pintle 9, thereby stopping the forward actuation of the loader and permitting said loader to return automatically to 95 starting position. The bucket 1 continues on its way, and, at any desired point in the system, the operator may, manually or automatically, trip the handle 47, which operation releases the latches 4, thus permitting the bucket to become inverted and to discharge its contents. The bucket, thereupon, rights itself, and, as the track 7 and traction cable 11 are endless, the bucket will in due time be returned to the loading station where it can be reloaded as above. When the hoppers are in 100 starting position (at the left, Fig. 1), they are filled by ore which runs down chute 14, gate 15 being opened just long enough to permit the hoppers to be filled. The ore is retained in hoppers 10, the mouth of the hoppers being closed by the bulkhead 31, but when the loader is moved toward the right, Fig. 2, mouths 30 of 110 hoppers 10 are carried clear of the bulkhead, and the ore thus permitted to drop into the buckets 1. At each succeeding operation the hoppers are recharged from chute 14, as before, so that the loading and unloading of buckets 1 and hoppers 10 becomes a continuous and 115 automatic operation, which is repeated *ad libitum*, or as long as the traction cable 11 is kept in motion.

Having thus described our said invention, what we claim and desire to secure by Letters-Patent is:

1. In an aerial tramway system, the combination of a 120 traveling bucket and a traveling loader, said loader embodying a plurality of hoppers which discharge into said bucket.
2. In an aerial tramway system, the combination of a 125 traveling bucket and a traveling loader, said loader embodying a pair of hoppers discharging into said bucket, one of said hoppers being on each side of the bucket.
3. In an aerial tramway system, the combination of a 130 traveling bucket and a loader traveling synchronously therewith, said loader embodying a plurality of hoppers which discharge into said bucket.
4. In an aerial tramway system, the combination of a

- traveling bucket and means for loading same while in motion, said loading means being actuated by said bucket and traveling a predetermined distance therewith and embodying a pair of hoppers, one hopper being on each side of the center of the path of travel of said bucket.
5. In an aerial tramway system, the combination of a traveling bucket, means for supporting same, and a loader embodying a plurality of hoppers for loading same, said loading means being actuated by said supporting means.
10. 6. In an aerial tramway system, the combination of a traveling bucket, means for supporting same, a loader embodying a plurality of hoppers for loading same, and means upon said loading means engaged by said supporting means and causing a forward movement of said loading means.
15. 7. In an aerial tramway system, the combination of a traveling bucket, a loader embodying a plurality of hoppers for loading same, means in connection with said traveling bucket for actuating said loading means, means upon said loading means engaged by said actuating means, and means for releasing said aforementioned means from engagement at a predetermined point.
20. 8. In an aerial tramway system, the combination of a traveling bucket having means for supporting same, a traveling loader, which embodies a plurality of hoppers, means projecting from said supporting means to actuate the loader, and means to stop said actuation at a predetermined point.
25. 9. In an aerial tramway system, the combination of a traveling bucket having means for supporting same, a traveling loader, a pintle projecting from said bucket-support to actuate the loader, and means to stop said actuation at a predetermined point.
30. 10. In an aerial tramway system, the combination of a traveling bucket, a traveling loader, said loader embodying two hoppers, and means for actuating said loader at a point between the hoppers.
35. 11. In an aerial tramway system, the combination of a traveling bucket, a traveling loader, said loader embodying two hoppers, and means whereby said traveling bucket actuates said traveling loader from a point between the two hoppers.
40. 12. In an aerial tramway system, the combination of a traction cable, a traveling bucket drawn thereby, a traveling loader, said loader embodying two hoppers, means cross-connecting said hoppers, and means actuated by the traction cable engaging said cross-connecting means, thereby to actuate the loader.
45. 13. In an aerial tramway system, the combination of a traction cable, a traveling bucket drawn thereby, a support for said bucket, a traveling loader embodying two hoppers, means cross-connecting said hoppers, and means connected to said bucket-support engaging said cross-connecting means, thereby to actuate the loader.
50. 14. In an aerial tramway system, the combination of a traction cable, a traveling bucket drawn thereby, a traveling loader embodying two hoppers, means cross-connecting said hoppers, a lever upon said cross-connection, and means actuated by the traction cable engaging the lever, thereby to actuate the loader.
55. 15. In an aerial tramway system, the combination of a traction cable, a traveling bucket drawn thereby, a traveling loader, a lever fulcrumed upon said loader, and means drawn by said traction cable and engaging the lever, thereby to actuate the loader.
60. 16. In an aerial tramway system, the combination of a traction cable, a traveling bucket drawn thereby, a support for same, a traveling loader, a lever fulcrumed upon said loader, and a member projecting from said bucket-support and engaging the lever, thereby to actuate the loader.
65. 17. In an aerial tramway system, the combination of a traction cable, a traveling bucket drawn thereby, a bucket support, a traveling loader, a pair of hoppers carried thereby, a shaft connecting said hoppers, a lever fulcrumed upon said shaft, and means drawn by the cable for engaging said lever, thereby to actuate the loader.
70. 18. In an aerial tramway system, the combination of a traction cable, a traveling bucket drawn thereby, a traveling loader, a pair of hoppers carried thereby, a shaft con-
- necting said hoppers, a spring-controlled lever fulcrumed upon said shaft, and means drawn by the cable engaging said lever, thereby to actuate said loader.
75. 19. In an aerial tramway system, the combination of a traction cable, a traveling bucket drawn thereby, a traveling loader, a pair of hoppers on the loader, a shaft between said hoppers, a lever fulcrumed upon said shaft, a spring encircling said shaft and having one end secured to said lever, and means drawn by the cable engaging said lever, thereby to actuate said loader. 85
80. 20. In an aerial tramway system, the combination of a traction cable, a traveling bucket drawn thereby, a traveling loader, a pair of hoppers on the loader, a shaft between said hoppers, a lever fulcrumed upon said shaft, a hook-like end upon said lever, means drawn by the cable and engaging said lever, said means causing same to rock about said shaft until said means seats in said hook, thereby to actuate said loader. 90
85. 21. In an aerial tramway system, the combination of a traction cable, a traveling bucket drawn thereby, a traveling loader, a pair of hoppers upon said loader, a lever supported between said hoppers, and means drawn by said cable and engaging the lever, thereby to actuate the loader. 95
90. 22. In an aerial tramway system, the combination of a traction cable, a traveling bucket drawn thereby, a support for same, a traveling loader, a pair of hoppers upon said loader, a lever supported between said hoppers, and a member projecting from said bucket support and engaging the lever, thereby to actuate the loader. 100
95. 23. In an aerial tramway system, the combination of a traction cable, a traveling bucket drawn thereby, a bucket support, a traveling loader, a pair of hoppers carried thereby, a shaft between said hoppers, a pair of levers fulcrumed upon said shaft, and means drawn by the cable for engaging said levers, thereby to actuate the loader. 105
100. 24. In an aerial tramway system, the combination of a traction cable, a traveling bucket drawn thereby, a traveling loader, a pair of hoppers carried by the loader, a shaft between said hoppers, a pair of spring-controlled levers fulcrumed upon said shaft, and means drawn by the cable and engaging said levers, thereby to actuate the loader. 110
105. 25. In an aerial tramway system, the combination of a traction cable, a traveling bucket drawn thereby, a traveling loader, a pair of hoppers on the loader, a shaft between said hoppers, a pair of levers fulcrumed upon said shaft, a pair of springs encircling said shaft, each of said springs having one end secured to one of said levers, and means drawn by the cable, engaging said levers, thereby to actuate said loader. 115
110. 26. In an aerial tramway system, the combination of a traction cable, a traveling bucket drawn thereby, a traveling loader, a pair of hoppers on the loader, a shaft between said hoppers, a pair of levers fulcrumed upon said shaft, a hook-like end upon the levers, means drawn by the cable and engaging the levers, said means causing said levers to rock about said shaft until said means seats in said hook, thereby to actuate the loader. 120
115. 27. In an aerial tramway system, the combination of a traveling bucket and a loader, said loader embodying a plurality of hoppers. 125
120. 28. In an aerial tramway system, the combination of a traveling bucket and a loader for loading same, said loader embodying a plurality of hoppers and being pushed forward from behind. 130
125. 29. In an aerial tramway system, the combination of a traveling bucket, a loader embodying a plurality of hoppers, means for connecting said loader to said bucket, and means for predeterminedly disconnecting same. 135
130. 30. In an aerial tramway system, the combination of a traveling bucket, a loader embodying a plurality of hoppers, and means upon the loader for causing same to move at a gradually increasing rate of speed. 140
135. 31. In an aerial tramway system, the combination of a traveling bucket, a two-hopper loader for loading same, and means upon the loader for causing same to move at a gradually increasing rate of speed, said means being carried between the hoppers. 145
140. 32. In an aerial tramway system, the combination of a traveling bucket, a two-hopper loader for loading same, 150

- and means upon the loader for causing same to move at a gradually increasing rate of speed, said means being carried between and supported by the hoppers.
33. In an aerial tramway system, the combination of a traveling bucket, a loader embodying a plurality of hoppers, and means upon the loader for causing same to move at a gradually increasing rate of speed, said means being engaged and actuated by the bucket-supporting means.
- 10 34. In an aerial tramway system, the combination of a traveling bucket, a two-hopper loader for loading same, and means upon the loader for causing same to move at a gradually increasing rate of speed, said means being carried between the hoppers and being engaged and 15 actuated by the bucket-supporting means.
35. In an aerial tramway system, the combination of a traveling bucket, a two-hopper loader for loading same, and a pair of levers upon the loader, said levers securing the actuation of the loader.
- 20 36. In an aerial tramway system, the combination of a traveling bucket, a two-hopper loader for loading same, a pair of spring-controlled levers upon the loader, said levers securing the movement of the loader, and means secured to the bucket support for actuating the lever.
- 25 37. In an aerial tramway system, the combination of a trolley beam supporting a traveling bucket, a traveling loader, and a member projecting from said beam, said member actuating said loader.
38. In an aerial tramway system, the combination of a 30 traveling bucket, a trolley beam supporting the same, a traveling loader, and a member projecting from said beam, said member supporting said bucket, and, also, actuating said loader.
39. In an aerial tramway system, the combination of a 35 traveling bucket, a triangular trolley beam supporting same, a traveling loader, sheaves being journaled in the beam adjacent two of the angles, and a member carried adjacent the third angle, said member supporting the bucket, and, also, actuating said loader.
- 40 40. In an aerial tramway system, the combination of a traveling loader, a cable, a shaft secured to the loader, a lever fulcrumed upon said shaft, and means drawn by the cable and engaging said lever, thereby to actuate the loader.
- 45 41. In an aerial tramway system, the combination of a cable, a traveling loader, a shaft thereupon, a lever fulcrumed upon said shaft, and means drawn by the cable and engaging said lever and causing said lever to rock upon said shaft, thereby to actuate the loader.
- 50 42. In an aerial tramway system, the combination of a cable, a traveling loader, a shaft thereupon, a lever fulcrumed on said shaft, and means drawn by the cable and engaging said lever and causing said lever to rock upon said shaft, said lever when thus rocked exerting a gradually increasing forward pressure on the shaft, thereby to actuate the loader.
43. In an aerial tramway system, the combination of a cable, a traveling loader, a shaft thereupon, a lever fulcrumed on said shaft, a spring intermediate said lever and said loader through which spring the forward pressure of said lever is communicated to the loader, and means drawn by the cable and engaging said lever and causing said lever to rock upon said shaft, thereby to actuate the loader.
- 60 44. In an aerial tramway system, the combination of a cable, a traveling loader, a shaft thereupon, a lever fulcrumed on said shaft, a spring intermediate said lever and said loader, said spring converting the upward pressure of the lever into forward pressure on the loader, and means drawn by the cable and engaging said lever and causing said lever to rock upon said shaft, thereby to actuate the loader.
- 70 45. In an aerial tramway system, the combination of a cable, a traveling loader, a lever pivoted upon said loader, means drawn by said cable and engaging said lever, and means for releasing said lever from such engagement at a predetermined point.
46. In an aerial tramway system, the combination of a cable, a traveling loader, a lever pivoted upon said loader, 75 a pintle drawn by said cable and engaging said lever, and means for releasing said lever from such engagement at a predetermined point.
- means for releasing said lever from such engagement at a predetermined point.
47. In an aerial tramway system, the combination of a cable, a traveling loader, a lever pivoted upon said loader, a hook upon said lever, a pintle drawn by the cable engaging said hook, and means for predeterminedly releasing said hook from said pintle.
- 85 48. In an aerial tramway system, the combination of a cable, a traveling loader, a spring-controlled pivoted lever upon said loader, the movement of said lever being communicated to said loader through said spring, and means to rock said lever, thereby to actuate the loader.
- 90 49. In an aerial tramway system, the combination of a cable, a traveling loader, a pivoted lever swinging in a vertical plane, a fulcrum therefor secured to said loader, and means to rock the lever, thereby to actuate the loader.
- 95 50. In an aerial tramway system, the combination of a cable, a traveling loader, a pivoted lever swinging in a vertical plane, a fulcrum therefor secured to the loader, a spring having one end secured to the lever and the opposite end secured to the loader, and means to rock the lever, thereby to actuate the loader.
- 100 51. In an aerial tramway system, the combination of a cable, a traveling loader, a spring-controlled lever pivoted thereupon, said lever having a hook-like end, a member drawn by the cable and engaging said lever, said member causing said lever to swing about its fulcrum until said member seats in said hook.
- 105 52. In an aerial tramway system, the combination of a cable, a traveling loader, a lever pivoted thereupon, said lever having a hook-like end, a member drawn by the cable and engaging said hook, and means for releasing said hook from engagement with said member.
- 110 53. In an aerial tramway system, the combination of a cable, a traveling loader, a lever pivoted thereupon, one end of said lever being hook-like, a member drawn by the cable and engaging said hook, and means engaging the end of said lever opposite said first-mentioned end, said means moving said lever and releasing said first-mentioned end from engagement with said member.
- 115 54. In an aerial tramway system, the combination of a cable, a traveling loader, a lever pivoted thereupon, one end of said lever being hook-like, a member drawn by the cable and engaging the lever adjacent its pivot, said member moving forward in a straight line and causing said lever to swing about its fulcrum until said member engages said hook-like end, and means for moving said lever still farther about its pivot, thereby to release said lever from engagement with said member.
- 120 55. In an aerial tramway system, the combination of a cable, a traveling loader, a shaft secured to the loader, a plurality of levers fulcrumed upon said shaft, and means drawn by the cable and engaging said levers, thereby to actuate the loader.
- 125 56. In an aerial tramway system, the combination of a cable, a traveling loader, a shaft thereupon, a plurality of levers fulcrumed upon said shaft, and means drawn by the cable and engaging said levers and causing said levers to rock upon said shaft, thereby to actuate the loader.
- 130 57. In an aerial tramway system, the combination of a cable, a traveling loader, a shaft thereupon, a plurality of levers fulcrumed on said shaft, and means drawn by the cable and engaging said levers and causing said levers to rock upon said shaft, said levers when thus rocked exerting a gradually increasing forward pressure on the shaft, thereby to actuate the loader.
- 135 58. In an aerial tramway system, the combination of a cable, a traveling loader, a shaft thereupon, a plurality of levers fulcrumed on said shaft, a spring intermediate said levers and said loader, through which spring the forward pressure of the levers is communicated to the loader, and means drawn by the cable and engaging said levers and causing said levers to rock upon said shaft, thereby to actuate the loader.
- 140 59. In an aerial tramway system, the combination of a cable, a traveling loader, a shaft thereupon, a plurality of levers fulcrumed on said shaft, a spring intermediate each of said levers and said loader, through which springs the forward pressure of said lever is communicated to the loader, and means drawn by the cable and engaging said

- levers and causing said levers to rock upon said shaft, thereby to actuate the loader.
60. In an aerial tramway system, the combination of a cable, a traveling loader, a shaft thereupon, a plurality of levers fulcrumed on said shaft, a spring intermediate said levers and said loader, said spring converting the upward pressure of the levers into forward pressure on the loader, and means drawn by the cable and engaging said levers and causing said levers to rock upon said shaft, thereby to actuate the loader.
61. In an aerial tramway system, the combination of a cable, a traveling loader, a plurality of levers pivoted upon said loader, means drawn by said cable and engaging said levers, and means for predeterminedly releasing said levers from such engagement.
62. In an aerial tramway system, the combination of a cable, a traveling loader, a plurality of levers pivoted upon said loader, a pintle drawn by said cable and engaging said levers, and means for predeterminedly releasing said levers from such engagement.
63. In an aerial tramway system, the combination of a cable, a traveling loader, a plurality of levers pivoted upon said loader, a hook-like end upon each of said levers, a pintle drawn by the cable and engaging said hooks, and means for predeterminedly releasing said hooks from said pintle.
64. In an aerial tramway system, the combination of a cable, a traveling loader, a plurality of spring-controlled pivoted levers upon said loader, the movement of said lever being communicated to said loader through the springs, and means to rock said levers, thereby to actuate the loader.
65. In an aerial tramway system, the combination of a cable, a traveling loader, a plurality of pivoted levers swinging in a vertical plane, a fulcrum for said levers secured to said loader, and means to rock said levers about said fulcrum, thereby to actuate the loader.
66. In an aerial tramway system, the combination of a cable, a traveling loader, a plurality of pivoted levers swinging in a vertical plane, a fulcrum for said levers secured to said loader, a spring having one end secured to the loader and the opposite end secured to the levers, and means to rock the levers, thereby to actuate the loader.
67. In an aerial tramway system, the combination of a cable, a traveling loader, a plurality of spring-controlled levers pivoted upon said loader, said levers each having a hook-like end, a member drawn by the cable and engaging said levers, said member causing said levers to swing about their fulcrum until said member seats in said hooks.
68. In an aerial tramway system, the combination of a cable, a traveling loader, a plurality of levers pivoted thereupon, said levers each having a hook-like end, a member drawn by the cable and engaging said hooks, and means for releasing said hooks from engagement with said member.
69. In an aerial tramway system, the combination of a cable, a traveling loader, a plurality of levers pivoted thereupon, one end of said levers being hook-like, a member drawn by the cable and engaging said hooks, and means engaging the ends of said levers opposite said hook-like ends, said means moving said levers and releasing said hook-like ends from engagement with said member.
70. In an aerial tramway system, the combination of a cable, a traveling loader, a plurality of levers pivoted thereupon, one end of said levers being hook-like, a member drawn by the cable and engaging the levers adjacent the pivots, said member moving forward and causing said levers to swing about their pivots until said member engages said hook-like ends, and means for predeterminedly moving said hook-like ends out of engagement with said member.
71. In an aerial tramway system, the combination of a cable, a traveling loader, a shaft thereupon, a plurality of levers fulcrumed on said shaft, a spring intermediate each of said levers and said loader, said spring converting the upward pressure of said levers into forward pressure on the loader, and means drawn by the cable and engaging said levers and causing same to rock about their pivots, thereby to actuate the loader.
72. In an aerial tramway system, the combination of a cable, a traveling loader, a traveling bucket, a support for same, and a guide upon the loader, said guide engaging the bucket support.
73. In an aerial tramway system; the combination of a traveling bucket, a traveling loader, a bucket support, a guide upon the loader above the bucket-support, said guide preventing undue upward motion of said bucket-support.
74. In an aerial tramway system, the combination of a loader, a hopper carried by said loader, and a bulkhead fixed at the loading station, said bulkhead being disposed in front of the mouth of said hopper and closing said mouth.
75. In an aerial tramway system, the combination of a traveling loader, a hopper carried by said loader, and a bulkhead, said hopper, while in one position, having its mouth closed by said bulkhead.
76. In an aerial tramway system, the combination of a traveling loader, a hopper carried by said loader, a bulkhead closing the mouth of the hopper, and means for drawing said hopper clear of said bulkhead so as to open the mouth of said hopper.
77. In an aerial tramway system, the combination of an ore chute, a traveling hopper, a stationary bulkhead closing the mouth of the hopper, a traveling bucket, means controlling the delivery of ore from said chute into said hopper, and means for drawing said hopper clear of said bulkhead, thus, to allow the ore to pass from said hopper into said bucket.
78. In an aerial tramway system, a traveling bucket, a traveling loader, a plurality of hoppers embodied in said loader and an inclined track upon which said loader travels.
79. In an aerial tramway system, a traveling bucket, a traveling loader for same, a plurality of hoppers embodied in said loader, means for actuating said loader, and means for automatically causing the return of said loader to starting position.
80. In an aerial tramway system, the combination of a traveling loader, a lever upon said loader, moving means engaged by one end of said lever, and means interposed in the path of travel of the end of said lever opposite said first-mentioned end, said means actuating said lever and releasing same from engagement with said moving means.
81. In an aerial tramway system, the combination of a traveling loader, a lever upon said loader, a hook-like end upon said lever, moving means engaged by said hook, and a trip interposed in the path of travel of said lever and engaging the end opposite said hook-like end, said trip depressing said lever and releasing said hook from engagement with said moving means.
82. In an aerial tramway system, a two-hopper loader having yielding contact means and movable means engaging said yielding means, thereby to actuate the loader.
83. In an aerial tramway system, the combination of a cable, a two-hopper loader, yielding contact means upon the loader, and means actuated by the cable for engaging said contact means.
84. In an aerial tramway system, the combination of a cable, a two-hopper loader, yielding contact means between the hoppers, and means actuated by the cable for engaging said contact means.
85. In an aerial tramway system, the combination of a cable, a two-hopper loader, traveling means carried by the cable to actuate the loader, yielding means upon the loader engaged by said traveling means, and means for releasing said yielding means from engagement with said traveling means.
86. In an aerial tramway system, the combination of a loader embodying a plurality of hoppers, means for moving the same, and means for returning the same to starting position.
87. In an aerial tramway system, the combination of a loader embodying a plurality of hoppers, means for moving the same, and a counterweight attached to the loader to return same to starting position.
88. In an aerial tramway system, the combination of a loader embodying a plurality of hoppers and an inclined track on which said loader travels.
89. In an aerial tramway system, the combination of a loader embodying a plurality of hoppers, an inclined track

- on which said loader travels, and a counterweight attached to said loader, and causing the automatic return thereof.
90. In an aerial tramway system, the combination of a cable, a traveling loader, a horizontal shaft upon said loader, an actuating lever which rocks upon said shaft, and means drawn by the cable for engaging said lever, thereby to actuate the loader.
91. In an aerial tramway system, the combination of a cable, a traveling loader, a traveling bucket, a support for same, and means upon said loader to limit the upward movement of said bucket.
92. In an aerial tramway system, the combination of a cable, a traveling loader, a horizontal shaft upon said loader, an actuating lever which rocks upon said shaft, means drawn by the cable for engaging said lever, thereby to actuate the loader, and means interposed in the path of travel of said lever predeterminedly to release same from the cable.
93. In an aerial tramway system, the combination of a cable, a traveling loader, a horizontal shaft upon said loader, a lever which rocks upon said shaft, means drawn by the cable for hooking with said lever, thereby to actuate the loader, and means interposed in the path of travel of said lever to unhook same from said loader.
94. In an aerial tramway system, the combination of a cable, a traveling loader embodying a pair of hoppers, a shaft countersunk in each of said hoppers, and means whereby said cable pulls upon said shaft, thereby to actuate the loader.
95. A bucket-loader comprising a framework approximately rectangular in shape, wheels supporting same, and a plurality of hoppers depending from said framework.
96. In an aerial tramway system, the combination of a bucket-loader comprising a framework and an open-mouthed hopper depending therefrom, and means at the loading station for closing the mouth of said hopper.
97. In an aerial tramway system, the combination of a bucket-loader, a pair of rails on which same travels, and means for actuating the loader, said means being disposed between said rails.
98. In an aerial tramway system, the combination of a bucket-loader, a pair of rails on which same travels, and a traction cable for moving said loader, said cable being disposed between said rails.
99. In an aerial tramway system, the combination of a bucket-loader, a pair of rails on which same travels, a lever supported by the loader between said rails, and a traction cable to pull said lever, thereby to actuate the loader.
100. In an aerial tramway system, the combination of a bucket-loader, a pair of rails on which same travels, front wheels and back wheels riding on said rails, and means for actuating the loader at a point midway between said front wheels and said back wheels.
101. In an aerial tramway system, the combination of a traveling bucket, a traveling loader, a pair of levers on the loader, and means engaging the levers, thereby to actuate the loader.
102. In an aerial tramway system, the combination of a cable, a traveling bucket, a traveling loader, a lever the axle of which is fixed to the loader, means drawn by the cable for engaging said lever, and means for predeterminedly releasing said lever from such engagement.
103. In an aerial tramway system, the combination of a cable, a traveling loader, a traveling bucket, a support for same, and means upon said loader above the bucket-support, said means limiting upward movement of said bucket-support.
104. In an aerial tramway system, the combination of a cable, a traveling loader having a yielding contact means, thereupon, and means actuated by the cable for engaging said contact means.
105. In an aerial tramway system, the combination of a cable, a traveling loader, a traveling bucket, and a guide adapted to limit upward movement of said bucket.
106. An aerial tramway system, the combination of a traveling loader, a hopper carried thereby, a bulkhead fixed at the loading station, and a brace for said bulkhead.
107. In an aerial tramway system, the combination of a traveling loader, a hopper carried thereby, and a bulkhead fixed at the loading station, said bulkhead having a flaring edge.
108. In an aerial tramway system, the combination of a traveling bucket, a hopper carried thereby, a bulkhead fixed at the loading station, said bulkhead having a flaring edge, and a brace member which engages said bulkhead at a point between said flaring edge and the edge opposite thereto.
109. In an aerial tramway system, the combination of a sliding ore-gate, a bell-crank in pivotal connection therewith, a rock-shaft, a link intermediate the rock-shaft and the bell-crank, and means to move the rock-shaft, thereby to move the ore-gate.
110. In an aerial tramway system, the combination of a sliding ore-gate, a rock-shaft, means intermediate the rock-shaft and the ore-gate, and means to rock the rock-shaft, thereby to move the ore-gate.
111. In an aerial tramway system, the combination of a cable, a traveling loader, a lever fulcrumed thereupon, said lever having a hook-like end, an inclined stop disposed in the path of travel of said lever, and a member drawn by the cable for engaging said hook, said stop being adapted to release said hook from said member.
112. In an aerial tramway system, the combination of a cable, a traveling loader, a lever fulcrumed thereupon, said lever having a hook-like end and bearing a roller at the opposite end, a member drawn by the cable and engaging said hook, and a stop interposed in the path of travel of said lever, said roller being adapted to ride on said stop, thereby to release said hook from said member.
113. In an aerial tramway system, the combination of a cable, a traveling loader, a pair of levers fulcrumed thereupon, means drawn by the cable and adapted to engage the levers, thereby to actuate the loader, and means cross-connecting the levers, to cause the same to move in unison.
114. In an aerial tramway system, the combination of a cable, a traveling loader, a pair of levers carried thereupon, means drawn by the cable and adapted to engage the levers to actuate the loader, a member cross-connecting said levers, rollers journaled on said member, and means interposed in the path of travel of said rollers to release the levers from said cable-drawn means.
115. In an aerial tramway system, the combination of a traveling bucket, a pair of material-feeding chutes, and a traveling hopper intermediate each chute and said bucket.
116. In an aerial tramway system, the combination of a traveling bucket, a pair of material-feeding chutes, a hopper, intermediate each chute and said bucket, means to load said hoppers from said chutes, and means to discharge said hoppers into said bucket while said hoppers are in motion.
117. In an aerial tramway system, the combination of a cable, a traveling bucket, a traveling loader, a spring-controlled lever on the loader, and means drawn by the cable and engaging said lever, thereby to actuate the loader.
118. In an aerial tramway system, the combination of a traveling loader, a traveling bucket, a bucket-support having a curved top, and a guide upon the loader against which said curved top bears.
119. In an aerial tramway system, the combination of a cable, a traveling loader having a pair of yielding contact members thereupon, and means actuated by the cable for engaging said contact members.
120. In an aerial tramway system, the combination of a cable, a traveling loader embodying a pair of hoppers, a pair of yielding contact members, one of said members being adjacent each of said hoppers, and means actuated by the cable for engaging said contact members.
121. In an aerial tramway system, the combination of a traveling bucket, a pair of material-feeding chutes, a hopper intermediate each chute and said bucket means to load said hoppers from said chutes while said hoppers are at rest, means at the loading station to retain the material in said hoppers, and means to move said hoppers away from said retaining means, thereby to discharge the hopper-contents into said bucket while said hoppers are in motion.
122. In an aerial tramway system, the combination of a bucket-loader, a pair of rails on which same travels,

- and a traveling bucket, the discharge from said loader into said bucket being located at a point intermediate said rails.
123. In an aerial tramway system, the combination of 5 a bucket-loader embodying a pair of hoppers, a pair of rails on which said loader travels, and a traveling bucket, the discharge of said hoppers into said bucket being located intermediate said rails.
124. In an aerial tramway system, the combination of 10 a bucket-loader, a pair of rails on which same travels, and a traveling bucket which travels in approximately the same direction as said rails extend, and intermediate said rails.
125. In an aerial tramway system, the combination of 15 a cable, a bucket-loader, a lever fulcrumed thereupon, said lever having a curved edge, and means drawn by the cable and adapted to engage said curved edge, thereby to actuate the loader.
126. In an aerial tramway system, the combination of 20 a cable, a bucket-loader, a pair of levers fulcrumed thereupon, said levers each having a curved edge, and means drawn by the cable adapted to engage said curved edges, thereby to actuate the loader.
127. In an aerial tramway system, the combination of 25 a cable, a bucket-loader, a pair of levers fulcrumed thereupon, said fulcra being in alinement, each of said levers having a curved edge, and means drawn by the cable, adapted to engage said curved edges, thereby to actuate the loader.
128. In an aerial tramway system, the combination of 30 a cable, a traveling loader, a pair of levers fulcrumed thereupon, said fulcra being in alinement, and means drawn by the cable and adapted to engage said levers, thereby to actuate the loader.
129. In an aerial tramway system, the combination of 35 a bucket-loader, a pair of rails on which same travels, and a traveling bucket, the discharge from said loader into said bucket being located at a point approximately midway between said rails.
130. In an aerial tramway system, the combination of 40 a bucket-loader, a pair of rails on which same travels, and a traveling bucket, said bucket being suspended intermediate said rails.
131. In an aerial tramway system, the combination of 45 a bucket-loader, a pair of rails on which same travels, and a traveling bucket, said loader being adapted to dis-
- charge into said bucket while said bucket is intermediate said rails.
132. In an aerial tramway system, the combination of 50 a traveling bucket, a traveling hopper on each side thereof, and means to load said hoppers.
133. In an aerial tramway system, the combination of 55 a traveling bucket, a traveling hopper on each side thereof, which hoppers discharge into said bucket, said hoppers being actuated by said bucket and being adapted to travel a predetermined distance therewith.
134. In an aerial tramway system, the combination of 60 a traveling bucket and loading means embodying a plurality of hoppers, one hopper being on each side of the bucket.
135. In an aerial tramway system, the combination of 65 a traveling bucket and loading means embodying a plurality of traveling hoppers, one hopper being on each side of the bucket.
136. In an aerial tramway system, the combination of 70 a traveling bucket, means for supporting same, and a plurality of traveling hoppers for loading same, one hopper being on each side of said bucket, said hoppers being actuated by said supporting means.
137. In an aerial tramway system, the combination of 75 a traveling bucket, a traveling hopper on each side thereof, and means for actuating said hoppers at a point intermediate the hoppers.
138. In an aerial tramway system, the combination of 80 a traveling bucket, a traveling hopper on each side thereof, and means for causing said hoppers to move at a gradually-increasing rate of speed.
139. In an aerial tramway system, the combination of 85 a traveling bucket, a traveling hopper on each side thereof, and a lever for each hopper to actuate same.
140. In an aerial tramway system, the combination of 90 a traveling bucket, a traveling hopper on each side thereof, means for connecting said hoppers to said bucket, and means for predeterminedly disconnecting same.

In testimony whereof we have affixed our signatures in 85 presence of two witnesses.

WALTER S. GEMMER.
EMIL J. SCHLEICHER.
